UNITED STATES PATENT OFFICE

160,010

COMBINED AIR CLEANER AND REGULATOR

Donald J. Peeps, Toledo, Ohio, assignor to The De Vilbiss Company, Toledo, Ohio, a corporation of Ohio

Application August 27, 1949, Serial No. 4,720

Term of patent 14 years

(Cl. D62—2)

To all whom it may concern:

Be it known that I, Donald J. Peeps, a citizen of the United States, residing at 3715 Maxwell Road, Toledo, in the county of Lucas and State of Ohio, have invented a new, original, and ornamental Design for a Combined Air Cleaner and Regulator, of which the following is a specification, reference being had to the accompanying drawing, forming part thereof.

In the drawing

Fig. 1 is a front elevational view of a combined air cleaner and regulator showing my new design;

Fig. 2 is a side elevation thereof; and Fig. 3 is a top plan view thereof.

I claim:

The ornamental design for a combined air cleaner and regulator, as shown.

DONALD J. PEEPS.
